United States Patent Office.

WILLIAM H. BURROWS, OF NEW YORK, ASSIGNOR TO JORDAN L. MOTT,
OF MOTT HAVEN, NEW YORK.

Design No. 4,970, dated June 6, 1871.

DESIGN FOR A RANGE.

The Schedule referred to in these Letters Patent and making part of the same.

To all whom it may concern:

Be it known that I, WILLIAM H. BURROWS, of the city, county, and State of New York, have invented and produced a new and original Design for the Front and Fire-Place end of a Cooking-Stove, which I term the "Dauntless," and of which the following is a description with reference to the drawings, in which—

Figure 1 is a perspective view of the stove;

Figure 2 is a profile section of the stove taken through the oven-door;

Figure 3 is a similar section taken through the feeder and ash-pit door; and

Figure 4 is a like section of the end of the stove.

Similar letters of reference indicate corresponding parts in both drawings.

On the base of the stove is a deep fillet, *a*, surmounted by an ovolو, *b*, above which is an ogee, *c*, surmounted by a fillet, *d*, above which is an ovolو, *g*, and another fillet, *r*, which is joined to the flat face of the stove by a hollow curve. These same moldings also extend along the edges and top of the front and sides of the stove, and are surmounted at the top by a cavetto, *g*, and ogee, *o*.

The edge of the top plate *B* consists of a fillet, *e*, surmounted by an ovolو, *f*.

The oven-door *C* is of rectangular form, having rounded upper corners, and is bounded by moldings *s*, whose form is shown distinctly in figs. 1 and 2, and having a bass-relief ornament, *t*, which is clearly represented in figs. 1 and 2 of the drawings.

The ash-pit door *D* curves outwardly toward its base, is bounded by moldings *u* whose shape is shown in figs. 1 and 3, and has a molding, *v*, surrounding the draught-wheel or disk in its lower portion, and above this a circular cup-like cavity, into which the end of the grate-spindle extends, and over which, arranged in the form of an arch, is the word "Dauntless."

Above this door is the feeder *F*, the door of which is inclined, and is bounded by moldings *w*, and furnished with a bass-relief ornament, *x*, similar, except that it is smaller, to the one, *t*, on the oven-door.

The draught-opening *G*, at the end of the stove, is raised from the face thereof, and is slightly inclined. It is bounded with moldings, *y*, the shape of which is shown in fig. 4. Above this draught-opening is a panel bounded by a bead and inclosing an ornament, *z*, similar, except in size, to those on the oven-door and the feeder.

The legs *L L* of the stove are made to correspond with the general design of the stove, and are ornamented with bass-relief figures *a'*, similar in general design to those on the body and doors of the stove.

What I claim as my invention, and desire to secure by Letters Patent, is—

The design for the front and fire-place end of a stove, herein shown and described.

WILLIAM H. BURROWS.
